UNITED STATES PATENT OFFICE.

LOUIS K. JOHNSON AND A. AUGUSTUS LOW, OF BROOKLYN, ASSIGNEES TO
THE ALDEN TYPE MACHINE COMPANY, OF NEW YORK, N. Y.

TYPE-DISTRIBUTING APPARATUS.

SPECIFICATION forming part of Letters Patent No. 360,096, dated March 29, 1887.

Application filed February 13, 1886. Serial No. 191,824. (No model.)

To all whom it may concern:

Be it known that we, LOUIS K. JOHNSON and A. AUGUSTUS LOW, citizens of the United States, residing in the city of Brooklyn, in the 5 county of Kings and State of New York, have invented certain new and useful Improvements in Type-Distributing Apparatus, of which the following is a specification.

Our improvements relate to the class of type-distributing apparatus in which the types are dropped by hand upon receiving-plates, which are formed with grooves through which the types pass to an intermediate conduit-plate, from which latter they are transferred to the 15 type-containing channels for use in the setter-case.

As heretofore constructed by us distributing apparatus has been made in the duplex form, a vibrating pusher being arranged between two series of type-containing channels, so as to forward the types alternately in each. The distributing apparatus has also been made double, in the sense that provision has been made for the accommodation of two complete 25 sets of receiving-plates, conduits, and containing-channels arranged with relation to a single vibrating pusher, the set being reversed in position upon opposite sides of the apparatus, so that two operators can work simultaneously, 30 but separate and independently.

In connection with our method of distribution each distributor is provided with a type-line separator, technically known as a "breaker," in which the columns of type to be distributed are placed, as fully set forth in Letters Patent No. 277,740, dated May 15, 1883. In order to facilitate the process of distribution it is desirable that these breakers should be so situated with relation to the receiving- 40 plates and the position of the operator that the hand of the latter can conveniently and naturally grasp and remove the types from the breaker and drop them into their respective cups or receivers in the said plates with the 45 least possible expenditure of time and movement.

A novel feature in our present construction of double distributor consists in an arch or bridge which extends diagonally over both 50 sets of distributing-receivers, and is formed with sockets for the reception of the vertical

trunnions formed upon the base of the breakers. By this means we are enabled to arrange the breakers directly over the receiving-plates and facing the operator, so that the hand of 55 the latter has only to travel a very short distance in order to procure fresh types for distribution. In this connection a novel feature of construction consists in the use of Italic or odd-sort line holders mounted upon the bridge 60 above mentioned, into which words or lines of Italics or other odd sorts not belonging to the style of type under distribution, and therefore not provided for in the receivers below, may be temporarily stored preparatory to their removal and distribution into their appropriate 65 channels or cases. These "line-holders" consist each of a removable tray formed with narrow grooves or compartments for the reception and support of the lines of type, and with lugs or 70 projections which engage notches in the supporting-racks attached to the bridge. The trays may be conveniently held in the left hand while distributing the type therefrom.

Another feature of our present construction 75 consists in providing each receiving-plate with an independent adjustable guard, situated over and projecting more or less into the receivers or cups, for the purpose of regulating the descent of the types upon their "flat" sides. 80 By making the guard adjustable with relation to the floors of the receivers we are enabled to adapt the receiving-plates to the distribution of various sizes of types.

The receiving-plates are stamped out of sheet 85 metal, and their lower extremities are bent or curved downward, so as to gradually change the angle of the types as they approach and enter the intermediate or vertical conduit-plates. Since this curve or bend is preferably 90 nearly equal in each plate, and since the plates are of different widths, it necessarily follows that when they are superposed they will come in contact with each other only at or near their upper and lower edges, as illustrated in Fig. 95 4, so that a space of varying area will be left between.

In order to insure the proper descent of the types through the channels in the receiving-plates, it is desirable that they shall be positively confined therein. This is especially the case as they approach the lower curved ends 100

of the plates, and to obviate all danger of displacement or derangement we employ in conjunction with each plate an intermediate or auxiliary plate, which rests snugly over the greater portion of the type-grooves, and by its projection more or less around the curved end of the plate governs the point at which the types are released. In order to more effectually regulate and control the release or discharge of the types from the lower curved ends of the receiving-plates, as just indicated, we make the intermediate or auxiliary plates adjustable upon the receiving-plates in such manner that their lower edges may be regulated in position with relation to the lower edges of the receivers.

In order to effect the accurate register or coincidence between the lower ends of the type-grooves in the receiving-plates with the appropriate type-conduits in either the face-plate or the vertical conduit-plates, against which they abut, we make the receiving-plates individually and independently adjustable longitudinally by means of set-screws or similar well-known means, by which the plates may be secured and held in the prescribed position after adjustment, thus also obviating all possible looseness or play. The importance of thus accurately securing and preserving the coincidence of all the type-passages will be obvious when it is considered that any deviation from such perfect alignment necessarily implies sharp corners or shoulders protruded in the path of the type, which tend to stop or derange the latter.

An important feature of our invention consists in providing the bank of receiving-plates with a common face-plate intermediate between their lower extremities and the front of the vertical conduit-plate, against which it abuts, said face or intermediate plate being formed with tongues or ridges, which form continuations of the receiver-plate-channel floors and project more or less into the conduits in the vertical plate, according to the thickness of the types to be distributed. Thus, for the smaller types, the tongues or projections are adjusted so as to project into the conduits to "zero" or to form the narrowest channel, while for the larger types they are withdrawn more or less in proportion to the increase in the size of the types.

We are aware that in our application No. 131,261, filed May 12, 1884, we show and describe tongues and continuations of the floors of the receiving-plate channels projecting into the conduits in the conduit-plates, and also means for regulating their position with relation to the latter, and we do not herein seek to claim such construction or adjustment, broadly, the novelty in the present case consisting in the use of a common intermediate plate formed with tongues or ridges which extend to the bottom of the conduit-plates or to the top of the front guard thereon, so that the conduits in the conduit-plates are completely covered and inclosed from the point of en-

trance of the type to the type-containing channels below. By this means the types are positively controlled from the time they leave the receivers or cups in the receiving-plates until they are deposited in the containing-channels. In this connection it may be stated that we also, when desirable, make the individual tongues or ribs upon the intermediate plate relatively of different degrees of projection, for the purpose of compensating for the difference in thickness of the several type characters contained in a single font or style of type on substantially the same principle that the pusher-comb teeth are made of various lengths in our application No. 171,366, filed July 11, 1885.

Our invention also includes a swinging guard or front plate arranged at the lower edge of the vertical conduit-plates just above the type-channels, which guard is adjustable horizontally with relation to the vertical conduit-plate, for the purpose of compensating for the differences in the thickness of the sizes or styles of type which it is required to distribute through the apparatus, the inner side of the guard being formed with projections or ribs annular to and corresponding with those formed upon the intermediate plate described above.

Heretofore, in our application for patent, No. 156,604, we have made provision for preventing the retractile movement or "backlash" of the types after they have entered the containing-channels, which means consists in a slight shoulder or deviation formed near the end of the type-containing channel sufficient to afford resistance against the return of the types after they have once been forwarded beyond that point.

The construction referred to is effective in preventing backlash in the columns of type beyond the said lateral deviation; but in some cases the lateral deviation in the type-containing channels may be objectionable, and even when such is not the case there is still necessarily a space between such deviation and the front of the conduit-plate, in which the latest types are apt to vibrate back and forth with the pusher until advanced in turn by the descent of the succeeding types. This vibration of the last type is apt to expose its head or face to the impact of the heel of the next succeeding type as the latter falls through the vertical conduit, thereby not only causing injury to the face of one type, but deranging the position of the other. We obviate this danger by means of a series of separate and independently-acting checks arranged immediately in front of the lower extremity of the vertical conduit-plate and just above the inner or receiving ends of the type-containing channels. Each conduit is provided with one of these checks, which act as an automatic gate, allowing a type to pass underneath it and into the type-containing channel while under the impulse of the type-forwarder, but resisting its return. By this means each type is checked and sustained

in a steady upright position practically as soon as it reaches the bottom of the vertical conduit, since the continuous vibratory movement of the forwarder will pass it beyond the gate 5 or check before another type can descend upon it.

Our present invention also embodies a new means for transferring the types from the vertical conduits into the type-containing channels and of forwarding them within the latter. Heretofore we have used a vibratory double-comb pusher for effecting this result, the teeth of which projected into and through the conduits at every vibration. Thus during a portion 15 of the time the lower extremity of each conduit was occupied by a rectangular moving floor or bottom, the motion of which tended constantly to derange types descending thereon, especially during the withdrawal of the pusher-tooth. We obviate this difficulty by making the lower extremity of each of the conduit-plates in the form of a hinged or swinging section having tongues or continuations of the conduit-floors, which, when the sections are 20 vibrated by suitable means, enter and forward the types in the type-containing channels. These movable lower sections of the conduit-plates may be made to vibrate back and forth by any suitable means, by linking them to a 25 plate made to reciprocate by means of a crank or eccentric, in the same manner as our old form of double-comb pusher. The extent of vibration is such that the tongues or extensions of the conduit-floors at one extremity of 30 the stroke are in line with the latter, while at the other extremity of the stroke their extreme lower ends project forward sufficiently to push the types the requisite distance into the type-containing channels. It will be observed that 35 by this arrangement a type descending during the forward movement of the forwarding tongues will encounter an inclined surface, which, instead of tending to cause rebound or derangement, will instead tend to gently check 40 or break the fall or inertia of the descending type and guide its heel squarely against the sides of the last preceding type, thus preventing its turning upon its longitudinal axis.

We are aware that in patents to Fraser, 45 Nos. 224,166 and 226,297, movable type-deflectors in the channels and loose vibratory tongues *d* in the ends of conduits are shown; but such features are not the equivalent of our invention in this respect, the essential feature 50 herein being the positive reciprocation of the lower ends of the type-conduits for the purpose of forwarding the types into the containing-channels direct, dispensing entirely with the independent reciprocating pusher, indispensible in the Fraser apparatus. The positive 55 vibration of the lower portions of our conduit-floors also obviates the danger of clogging or retardation of types, which is liable to occur in practice where a weighted obstruction 60 projects continuously in the path of the descending types.

In the accompanying drawings, Figure 1 is

a plan of a duplex type-distributing apparatus, showing the relative arrangements of parts upon the bed of the apparatus, one of 70 the receiving-banks being withdrawn from its conduit-plate. Fig. 2 is an elevation of the same, showing the lower portions of the breaker-standards in position upon the bridge. In both Figs. 1 and 2 the minor details of construction—as the receivers, grooves in the conduit-plates, &c.—are omitted, since the general construction is the same as that shown and described in our last application, No. 171,366, to which reference may be had. Fig. 3 is a 80 plan of one of the type-receiving plates and its auxiliary plate or cover and a horizontal section of the vertical conduit-plate adjoining. Fig. 4 is a front view of the receiver face-plate, showing the offsets, which conform to the 85 differences in position vertically between the ends of the type-channels in the receiver-plates, and showing the tongues or ribs which form continuations of the said channel-floors. Fig. 5 is a transverse section of a receiver-plate on plane of line *a a*, Fig. 3, showing the 90 adjustable type-guard. Fig. 6 is a vertical sectional view of three superposed type-receiving plates and the adjoining portion of the vertical conduit-plate; Fig. 7, a front view of 95 one of the vertical conduit-plates with lower guard, and Fig. 8 a top view of the same; Fig. 9, a vertical section, upon a larger scale, of the lower end of a vertical conduit with 100 individual checks or gates, &c., and adjoining parts; Figs. 10, 11, and 12, sectional views illustrating the construction of the individual type-checks; Fig. 13, a vertical section through the conduit-plates, &c., showing means for 105 forwarding the types; Figs. 14, 15, and 16, detail views of the new form of type-containing channels. Fig. 17 is a front elevation of the lower vibrating section of the conduit-plate; Fig. 18, a vertical section similar to Fig. 9, showing a modification in the form of individual check; Fig. 19, a sectional view upon plane of line *z z*, Fig. 18, further illustrating 110 such modified construction.

In general construction and operation our apparatus is substantially the same as that 115 shown and described in our last application, No. 171,366, filed July 11, 1885, for patent upon this subject, two complete cases, *C C'*, being arranged upon one bed, *A*, the cases being reversed in position and arranged upon 120 opposite sides of the bed *A*. The vertical conduit-plates *B B*, arranged back to back and extending centrally across the bed *A*, are also common to the application named, as is the general arrangement of the superposed receiving-plates *R* upon sliding carriages or frames *R'*. Extending diagonally over, across, and between the two cases *C* and *C'* is an arch or bridge, *D*, secured to suitable standards, *D' D'*, mounted upon opposite ends of the bed *A*. In 125 positions adjoining to and above the receiving-plates *R*, when in position against the vertical conduit-plates *B B*, the bridge *D* is formed with sockets *d d*, for the reception of the ver-

tical trunnions *e*, which project from the under sides of the breaker-standards *E*, the breakers not being indicated in the drawings, since they form no part of our present invention, 5 being the subject of Letters Patent No. 277,740. The sockets or bearing are preferably provided with set-screws *d'*, for securing each breaker in the desired position.

Mounted upon the bridge within convenient reach of the operators are racks *II*, into which fit trays *JJ*, which are formed with lugs *j j*, which enter notches *i i*, formed in the racks *I*, when the trays *JJ* are placed in position. Each tray is formed with a series of 15 grooves or compartments, *j' j'*, for the reception of lines of type. As before indicated, the trays are designed for the temporary storage and transfer of words or lines of Italic or other odd sorts of types. By thus arranging both 20 the breakers and the "odd-sort" trays upon the bridge *D* the operator is not required to leave his position in front of the receiving-plates *R* for the purpose of securing matter for distributing, or on account of the occurrence 25 of characters for which no provision exists in the case proper.

The receiving-plates *R* are made of sheet metal, shaped under pressure, with the usual series of cups or receivers, *r*, and conduits *r'*. 30 Extending across the upper part of each plate, and above the lower parts of the receivers or cups *r*, we arrange adjustable guards *V*, formed with tongues or extensions which project downward into the receivers *r* more or less, according 35 to the thickness of types to be distributed. The adjustment may be effected in any convenient manner, the means shown in the drawings consisting in set-screws *v v* at either extremity, which screw into the receiving-plates, with intermediate binding-screws, *v'*, which bear against the surfaces of the plates, and thereby lock the device in the position allowed by the set-screws.

Heretofore, as in our application No. 131,261, 45 filed May 12, 1884, we have made provision for regulating the descent of the types upon their flat sides by projections entering the cups or receivers; but in such case the projections formed a part of the receiving-plates above, the 50 plates themselves being relatively adjustable. We do not seek to cover herein, broadly, an adjustable guard at this point; but since it is not always desirable to make the plates adjustable, we have designed a separate and distinct guard for the purpose, which is independently adjustable. As heretofore, the plates *R* are supported upon the carriage *R'* between posts *R²* or other means of lateral support, their lower edges resting against the rear side 55 of the face-plate *F*.

At points coinciding with the positions of each of the several receiving-plates *R* set-screws *r³ r³* pass through the posts, so that they may be made to bear against opposite ends of the 60 plates and afford a means of adjusting the channels *r* in the latter into accurate registration with the tongues or ribs *f* in the face-plate *F*,

and hence with the conduits *b* in the vertical plates *B*, and maintaining such relation of parts. This arrangement is illustrated in Fig. 3, although it is obvious that other means of adjustment may be used with like result in lieu of the set-screws shown.

The face-plate *F* is secured to or formed upon the front of the carriage *R*, and is formed with a series of offsets, *f'*, as shown in Fig. 4, corresponding in position to the lower ends of the receiver-channels *r* in the receiver-plates *R* at the rear thereof. Ribs or tongues *f f* commence at the top of each step or offset *f'*, where 80 they coincide in position with and form continuations of the floors of the said type-channels *r*, from which point they extend downward to the bottom of the face-plate *F*. These ribs *f* project more or less into the conduits *b* in the vertical conduits *B* when the carriage *R* is moved forward until stopped by contact with adjustable buffers *H*, or other means for regulating the distance to be maintained between the face-plate *F* and the conduit-plate *B*. The ribs *f* are preferably made relatively of different degrees of projection from the face-plate *F*, according to the thickness of the particular characters of type that are to pass over them, so that the inclosed spaces or channels 95 formed between them and the bottoms of the conduits *b* in the vertical conduit-plates will be but slightly larger in cross-section than the cross-section of such types. This is shown in Fig. 3. The carriages slide back and forth upon parallel ways or in grooves *r⁴ r⁴*, formed upon the bed *A* of the apparatus.

Owing to the difference in width of the several receiving-plates and to their curved form, there is a space, *s*, formed between the adjoining plates when they are superposed, as indicated in Fig. 6.

In order to protect and confine the types during their passage through the channels *r*, we therefore provide each receiving-plate with an auxiliary plate or cover, *S*, which conforms to and rests snugly upon the top of the receiving-plate below. The lower edges, *s'*, of these intermediate plates or covers, *S*, terminate a short distance above the lower extremities of the receiving-plates. Below the edges of the covers *S* the types are free to assume vertical positions as they enter the conduits *b* in the vertical plates *B*. It is therefore obvious that the position of the lower edges, *s'*, of the covers *S* will have a controlling effect upon the descent of the types, and for this reason we make the covers *S* adjustable to a slight extent upon their respective receiving-plates, as illustrated, for instance, in Fig. 3, by the use of set-screws *s²*, passing through elongated slots *s³*, formed in the covers *S*. By this means we are enabled to regulate the position of the lower edge, *s'*, of each cover *S* accurately with reference to the size and style of type in use, so as to control the drop or fall into the conduits. The plates *R* and *S* are held down upon the carriage *R'* by screw-nuts *r⁶*, which engage threads formed upon the upper extremities of the posts *R²*.

In front and at the lower extremity of the vertical conduit-plates, and below the position of the lower edge of the face-plate F, when in position against the conduit-plate, we arrange 5 a foot-guard, G, which extends down to the type-containing channels L. This guard is preferably held in position in such manner that it may be swung upward or out of position, as shown in Fig. 7. It is also desirable 10 to make it adjustable with relation to the face of the conduit-plate, for the purpose of adapting the apparatus to different sizes of type, the inner side of the guard G being formed with tongues or projections g g, which correspond to 15 and coincide with ribs f upon the face-plate above. This may be done without preventing its being swung out of position, as above stated, when necessary to gain access to the lower parts of the conduits b, by supporting it at 20 either extremity between the ends of two opposed screws, g' g', as shown in Figs. 7 and 8. Thus, by retracting one screw and advancing the other at either end, the guard may be varied slightly in position with relation to the face of 25 the conduit-plate, and by using pointed screws g' g', entering slight depressions at one end of the guide G, the latter may, by slightly loosening one of the screws at the other extremity, be readily swung outward and upward, as indicated in Fig. 7. This guard G may consist 30 of a plain strip of metal, as shown in Figs. 7 and 8; but we prefer to form it with a series of compartments or recesses, g' g', which coincide in position with the conduits b in the 35 vertical conduit-plates B. In these recesses g' g' are situated small balls g' g', which rest in and project partially through smaller circular openings or seats, g' g', formed in the under side of the guard G. The lower portions of 40 the balls thus protruding through the lower portion of the guard G are directly in the path of the heads of the types as they are transferred into the mouths of the type-containing channels L by the type-forwarding mechanism.

When a type is advanced under the action of the forwarder, its head encounters the protruding portion of the ball opposite that particular conduit b, and elevates the ball in its 45 recess while passing underneath, when the ball again falls back upon its seat and acts as a check to resist any tendency on the part of the type to follow or fall back after the forwarder during and after the retractile movement of the latter.

The balls g' g' may be free to revolve in any direction, so that they readily adapt themselves to contact from any angle, and as they roll over the faces of the types all objectionable friction is avoided, and the faces of the types are preserved from wear or injury.

It is to be observed that the resistance afforded by a comparatively small light ball will be sufficient to sustain the type in an upright 65 position until forwarded by the advance of succeeding types, since the back-pressure exerted by a type in a vertical or nearly verti-

cal position will be comparatively slight, the last types being relieved of the back lash or pressure of the column of the type in the containing-channel by the shoulder or deviation 70 in the containing-channel itself, as in our application No. 156,604.

The balls may be made of cork, pith, or other soft material, or of harder material rendered smooth upon the surface, and where the weight of one would be insufficient to sustain the type, two or more may be placed in one recess, resting one upon the other; or the same result may be effected by the use of a light 75 spiral spring, as illustrated in Fig. 12. Instead of the balls shown, the checks may consist of small wheels arranged so that their peripheries will revolve in the direction of the type-channels, and having their axes resting 80 in elongated vertical slots, which will permit of the vertical movement of the checks. This modified form of individual check is shown in Figs. 18 and 19, in which the axes x of the disks g' rest upon seats formed at the bottoms 85 of the vertical grooves g', provided in the guard G.

It is to be observed that each check or gate is separate and independent of the others, both in situation and operation, so that they 90 may be designated as "individual" checks, G', the majority of which are at rest while the others are in operation. By this means the last types are sustained continuously until forwarded, whereas in the case of a single 95 common gate or check similar to that shown in our application No. 156,604 the last preceding types in all the channels were unsustained while the check was elevated to allow the entrance of succeeding types into a few 100 only of the channels.

For the purpose of avoiding all open spaces, sharp corners, &c., and rendering the sides of the type-passages uniform and continuous throughout, we make the receiving ends of 105 the containing-channels with side walls of uniform height, so that both said walls will reach up to and form continuations of the conduit side walls. The rest of each channel is formed with a low or narrow wall upon one side, (the 110 side which constitutes the face when in the setter-case, and from which the types are drawn transversely,) as heretofore, for the purpose of exposing to view and giving access to the types contained in the channels.

In lieu of the old form of double vibrating comb-pusher, the types are transferable to and forward in the channels by the lower extremities of the conduit-floors, which in this case are made to vibrate back and forth for the purpose. In order to effect this with simplicity we make each conduit-plate B in two sections, the upper one, b', stationary, as heretofore, while the lower section, b'', is pivoted or hinged to or in connection with the upper one, b', by 125 means which will permit of its vibration thereon without interfering with the continuation of the conduit-floors.

The lower ends of the conduit-floors have

heretofore been extended so as to project into the receiving ends of the type-containing channels, and have also been used as type-forwarders, as in the application for patent of A. 5 Augustus Low, No. 159,693, in which a combined type receiver and forwarder is reciprocated longitudinally by hand upon a type-containing channel; but in the present case the invention consists in forming the conduit- 10 plate in two parts, pivotally connected, the lower part, b^2 , being made to vibrate continuously and mechanically independent of the upper part, b' , which is stationary under all circumstances. The lower edge of the lower 15 section, b^2 , is in the form of a comb, the teeth of which constitute continuations of the floors of the conduits b above, while the spaces between afford accommodation for the side walls of the type-containing channels below. 20 The vibration of the lower sections, b^2 , of the conduits may be effected either directly or indirectly by any suitable means, that shown in the drawings consisting in connecting them by means of links p with a plate, P , which is reciprocated by cranks or eccentrics Q through the medium of a pitman, q . This pusher-plate P in construction and operation is substantially the same as our old form of pusher, except that it has no pusher-teeth and simply 25 transmits its motion to the lower ends of the conduit-plates, which act in lieu of the said pusher-teeth. By this means we not only obviate any evil effects of the descent of the types upon the type-forwarder, but also economize 30 in the cost of the apparatus, since the two rows of pusher-teeth formerly necessary are dispensed with.

As shown in the drawings, the vibrating lower sections, b^2 , of the conduit-plate B are 40 formed by rigidly securing the tongues (or prolongations of the conduit-floors) b^3 to the rock-shaft b^4 , pivotally suspended at the rear of the conduits and at opposite extremities thereof, so that the links p may be connected 45 to any of the tongues b^3 or to a crank-arm at either extremity, the result being the same.

What we claim as our invention, and desire to secure by Letters Patent, is—

1. In a duplex type-distributing apparatus, 50 substantially such as described, the diagonal bridge $D D' D'$, secured to the table of the apparatus and formed with the sockets $d d$, for the purpose and substantially in the manner described.

55 2. In a duplex type-distributing apparatus, substantially such as described, the diagonal bridge $D D' D'$, secured to the table of the apparatus and formed with the inclined brackets I , for the purpose and substantially in the 60 manner described.

3. The rack I , formed with the notches i , in combination with the type-tray J , formed with the lugs j , for engaging with the said notches i , for the purpose and substantially in 65 the manner described.

4. In a type-distributing apparatus, substantially such as herein designated, the com-

bination, with a receiving-plate, of an independent adjustable guard for the purpose of regulating the passage of the types from the 70 receivers or cups into the type-channels, substantially in the manner and for the purpose described.

5. In a type-distributing apparatus, substantially such as herein designated, in combination with a type-receiving plate, R , formed with the receivers r and channels r' , the guard V , formed with tongues which project downward into the receivers, and attached to the receiving-plate by set-screws $v v$ and binding-screw v' , substantially in the manner and for the purpose described. 75

6. In a type-distributing apparatus, substantially such as described, the combination, with a type-receiving plate formed with receivers and channels, substantially as described, of a cover or auxiliary plate for enclosing the said channels, substantially in the manner and for the purpose described. 85

7. In a type-distributing apparatus, substantially such as described, the combination, with a type-receiving plate formed with receivers and channels, substantially as designated, of a cover or auxiliary plate which is adjustable upon the said type receiving plate, 95 for the purpose and substantially in the manner described. 90

8. In a type-distributing apparatus, substantially as described, the combination, with the superposed receiving-plates, arranged and mounted upon a carriage or frame, substantially as designated, of means for adjusting the said plates individually and laterally, for the purpose and substantially in the manner described. 100

105 9. In a type-distributing apparatus, substantially such as designated, in combination with a series of superposed type-receiving plates formed with receivers and channels and mounted upon a common frame or carriage, 110 substantially as designated, a common face-plate formed with a series of tongues or ribs which form continuations of the floors of the type-channels formed in the said plates, the whole arranged and operating substantially 115 in the manner and for the purpose described.

11. In a type-distributing apparatus, substantially such as designated, a series of type-receiving plates provided with a common face-plate formed with continuations of the type-channel floors, the tongues or ribs which form such continuations being made of different degrees of projection corresponding to the difference in thickness between the characters of type, in combination with a conduit-plate, into 120 the type-channels of which projections or ribs protrude, substantially in the manner and for the purpose described. 125

130 11. In a type-distributing apparatus, substantially such as designated, the combination, with a series of superposed type-receiving plates provided with a common face-plate formed with projections or ribs which constitute continuations of the floors of the type-

channels in the said receiving-plates, and with a conduit-plate, into the channels of which the said projections or ribs upon the face-plate enter, substantially as described, of means for 5 regulating and adjusting the positions of the said face-plate and conduit-plate with relation to each other, substantially in the manner and for the purpose described.

12. In a type-distributing apparatus, substantially such as designated, in combination with a series of superposed receiving-plates mounted upon a common carriage or frame and provided with a common face-plate, and in combination with a conduit-plate for 15 receiving the types from the said receiving-plate, a guard arranged upon the front of the said conduit-plate below the lower edge of the receiver face-plate, substantially in the manner and for the purpose described.

13. In a type-distributing apparatus, substantially such as described, in combination with a series of superposed type-receiving plates provided with a common face-plate, substantially as described, and with a vertical conduit-plate for receiving the types from the said face-plate, a guard secured to the lower front part of the said vertical conduit-plate by means, substantially such as described, which permit of its being swung vertically out of position, 25 for the purpose and substantially in the manner described.

14. In a type-distributing apparatus, substantially such as designated, the combination, with a series of superposed type-receiving plates provided with a common face-plate, substantially such as described, and with a vertical conduit-plate for receiving the types from the said face-plate, and a guard situated below the said face-plate and at the lower 35 extremity of the said vertical plate, of means, substantially such as described, for adjusting the said guard horizontally with relation to the vertical conduit-plate, for the purpose and substantially in the manner described.

15. In a type-distributing apparatus, substantially such as described, in combination with a series of superposed type-receiving plates provided with a common face-plate, substantially as described, and in combination 45 with a conduit-plate for receiving the type

from the said face-plate, a guard situated in front of the lower portion of the conduit-plate and formed with tongues or projections which enter the conduits in the conduit-plate, said tongues being formed of different degrees of 55 projection to conform to the tongues or ribs upon the face-plate above, substantially in the manner and for the purpose described.

16. In a type distributing apparatus, substantially such as designated, in combination with a conduit-plate adapted to conduct the types into the type-containing channels below, and in combination with mechanism for forwarding the types in the said type-containing channels, a series of separate and independent 60 type checks or gates situated at the lower front side of the conduit-plate for the purpose of preventing any retractile movement in the types, substantially in the manner and for the purpose described.

17. In a type-distributing apparatus, substantially such as designated, in combination with a conduit-plate adapted to conduct the type into type-containing channels below, and in combination with mechanism for forwarding the types in said type-containing channels, a series of separate and independent type checks or gates situated at the lower front side of the conduit-plate, consisting of a series of 65 balls arranged in a series of recesses or compartments in such manner that portions of their peripheries project downward into the paths of the types to be forwarded, for the purpose and substantially in the manner described.

18. In a type-distributing apparatus, substantially such as described, the combination of a series of type-containing channels, a vertical type-conduit plate, the upper portion of which is stationary and the lower portion of 70 which is pivotally connected to the upper portion, and a reciprocating plate and connecting rod for vibrating the said lower section, substantially in the manner and for the purpose described.
